The ornamental design for a self regulating fluid bearing high pressure rotary nozzle, as shown and described.

(22) Filed: **Feb. 22, 2010**

DESCRIPTION

Related U.S. Application Data

(62) Division of application No. 12/577,571, filed on Oct. 12, 2009.

FIG. 1 is a perspective view of a self regulating fluid bearing high pressure rotary nozzle showing my new design.

(51) **LOC (9) Cl.** **23-01**

FIG. 2 is a rear perspective view of my new nozzle design.

(52) **U.S. Cl.** **D23/213**

FIG. 3 is one side elevational view of the nozzle shown in FIGS. 1 and 2, the opposite side elevational view being substantially identical thereto.

(58) **Field of Classification Search** D23/213,

FIG. 4 is a side elevational view of the nozzle shown in FIGS. 1 and 2 rotated clockwise about its longitudinal axis 90 degrees from the view shown in FIG. 3.

D23/214; 239/251, 259, 225.1

FIG. 5 is a top plan view of the front end of the nozzle shown in FIGS. 1 and 2.

See application file for complete search history.

FIG. 6 is a bottom plan view of the rear end of the nozzle shown in FIGS. 1 and 2; and,

(56) **References Cited**

FIG. 7 is a cross-sectional view taken along line 7—7 of FIG. 1. The broken lines show portions illustrating environmental structure of the nozzle that form no part of the claimed design.
